(57) **CLAIM**

The ornamental design for a curtain driver, as shown and described.

DESCRIPTION

FIG. 1 is a perspective view of a curtain driver, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is an enlarged view of FIG. 5 thereof.

The evenly broken lines where present illustrate portions of the curtain driver that form no part of the claimed design.
